UNITED STATES PATENT OFFICE.

ROBERT MORGENEIER, OF WINONA, MINNESOTA, ASSIGNOR TO THE AMERICAN CARVING AND MANUFACTURING COMPANY, OF SAME PLACE.

DUPLICATING-MACHINE.

SPECIFICATION forming part of Letters Patent No. 509,931, dated December 5, 1893.

Application filed November 11, 1892. Serial No. 451,665. (No model.)

To all whom it may concern:

Be it known that I, ROBERT MORGENEIER, of Winona, Minnesota, have invented certain new and useful Improvements in Duplicating Machines, of which the following is a specification.

The object of this invention is to provide a machine by means of which the most elaborate and artistic carvings and sculpturings, as well as any concrete object, may be automatically reproduced or duplicated; or, as in case of a carved or sculptured design, such design may, in the duplicate thereof, be cut deeper or shallower than the original, as may be desired; the model, and a single operation of the machine, being sufficient to reproduce an exact duplicate, or a deeper or shallower one. The patterns employed may be of any material capable of sustaining a slight pressure.

The duplicating machine comprises a main frame, a reciprocating table, a series of reciprocal and independently gyratory guide fingers, a projecting and retracting mechanism arranged in connection with said guide fingers; a series of revolute and reciprocal cutters arranged in connection with the guide fingers; a means for reciprocating the table; a means for revolving the cutters; means for permitting an independently gyratory and retractive motion in the guide fingers; holders for the pattern and material in which the pattern is to be reproduced in its normal, greater, or less, depth, and a means for imparting a corresponding movement to the pattern and material, such movement being practically universal.

In the accompanying drawings, Figure 1 is a plan view of my improved duplicating machine, the two top clamping pieces of the vertical standards being removed. Fig. 2 is a side elevation of the machine with parts broken away in order to more clearly exhibit the pattern. Fig. 3 is an elevation of the machine from the opposite side to that shown in Fig. 2. Fig. 4 is a front view. Fig. 5 is a plan view, partly in section, of the cutter and guide finger mechanism. Figs. 6 and 7 are enlarged detail views of the belt shifting mechanism, and Fig. 8 is a sectional detail view of the guide finger holder. Fig. 8^a is a

perspective view showing means for manually adjusting the pattern and material or pattern holders vertically.

In the drawings, A represents the main frame of the machine which serves to carry the various shafts and gears, the sliding table and the cutter and guide finger mechanisms necessarily employed in the construction of my machine. The main shaft of the machine is shown at 1. On one end of this shaft are mounted the loose pulley 2 and the two driving pulleys 3, 4. A straight belt and a quarter-turn belt run alternately, first on the loose pulley 2 and driver 4, and then on driver 3 and loose pulley 2, such alternation continuing during the operation of the machine. In organizing the machine in its present form the pulleys 2, 3 and 4 are each fourteen inches in diameter.

In proper position on shaft 1 is mounted the four inch gear 5, meshing with the twenty-four inch gear 6, mounted on shaft 7. On shaft 7 is also rigidly mounted the four inch gear 8, meshing with the thirteen inch gear 9 on shaft 10. On shaft 10 is mounted the four inch gear 11 meshing with the ten inch gear 12 mounted on shaft 13. Gear 12 engages the teeth of the rack 14 formed within the sliding table 15.

From the above described construction it will be seen that if the shaft 1 be driven at the rate of one hundred and fifty revolutions per minute, the four inch gear thereon will revolve the twenty-four inch gear 6, twenty-five times per minute; the four inch gear 8 on the same shaft with gear 6 will revolve the gear 9 on shaft 10, seven and seven tenths times per minute; the gear 11, also on shaft 10, will revolve gear 12, on shaft 13, three times per minute, and gear 12 engaged with the rack 14 on table 15, will cause such table to advance at the rate of ninety-six inches per minute, approximately; and when as before stated, the shaft 1 is caused to alternate in the direction of its revolution, because of the arrangement of the loose pulley 2 and drivers 3 and 4 and straight and quarter turn belts working on the one or the other of the drivers and on the loose pulley, then the table 15 will reciprocate at the rate of speed mentioned, *i. e.*, ninety-six inches per minute approximately. Thus

the object of the train of gears described is to transmit the power required to reciprocate table 15 continually during the operation of the machine.

- 5 Bolted against the side of the main frame A, at B, is the belt shifting device, consisting of the ways 16, in which is held and slides the piece 17. Formed in the sliding piece 17 is the flattened U-shaped slot 18, best shown in Fig. 1 and Fig. 7. On one end and on the upper surface of piece 17 is formed the lug 19 which is straddled by the lever 20. 21 and 22 are bell crank shifting levers pivoted at their angles and the inner ends of these levers overhang the sliding piece 17 and are provided with studs projecting downward into the slot 18. The outer or longer arms of the levers 21 and 22 have studs which upwardly project into the transverse slots 23 in the blocks 24. 15 Blocks 24 slide on the rods 25 and 26 and have formed on their lower sides projecting prongs or fingers 27, 27 which reaching downward straddle the belts carried over the pulleys 2 and 3 when the table is advancing in one direction and 2 and 4 when retreating. 20 Upon the lower left hand side of table 15 is formed or secured the T-rail 28. Adjustably mounted on the rail 28 are the two strikers 29 and 30. The striker 29 is so 25 shaped that when coming in contact with the rocking lever 20, it will strike it at a point above the center of the shaft upon which it is mounted. Striker 30 on the other hand will strike such lever in opposition and below the center of the shaft upon which it is held. From the construction above described it will be seen that if strikers 29 and 30 are securely clamped at any desired point upon rail 28 and the table is then caused to move 30 either forward or backward, one or the other of the strikers will encounter the lever 20. The momentum of the table exerted upon such lever will cause it to swing on its shaft and acting on lug 19 formed on piece 17 cause 35 such piece to slide in the ways 16; when the piece 17 is moved the levers 21, 22 will swing upon their pivots. The upward projecting studs of the levers moving in the slots 23 of the sliding blocks 24, will cause such blocks 40 to slide upon the rods 25, 26 and, as the prongs of blocks 24 straddle the belt running over the loose pulley 2 and the belt on one of the drivers of shaft 1, these belts will be shifted. One of these belts being straight 45 and the other crossed, the strikers 29 and 30 acting upon the lever 20 causes the reciprocating motion of the table 15. If the strikers are brought toward each other the reciprocative motion of the table 15 will be shorter and 50 if clamped at the extreme ends of rail 28 the greatest distance of reciprocation is secured. On the top of the reciprocating table 15 are formed the four inwardly beveled ways a, a, a, a in which slide the bases of the four standards 31, 32, 33 and 34. Standards 31 and 32 are rigidly connected by the frame piece 35 and the standards 33 and 34 are similarly

connected. These standards, so connected, constitute frames which are vertical, parallel and face each other and which are adjustable to and from each other along the ways a. The frame upon the left side of the table carries a pattern holder 36, which is vertically adjustable on and also vertically movable with the X-shaped bars 37, one section of which holds 75 said frame and the other section slides vertically in V-shaped grooves in said standards. The bars 37 are clamped to the holder by means of the bolts 37^a, and the vertical reciprocations of the holder are effected through said 80 bars. The holder is also manually adjustable on the bars 37 in order to enable the reproduction of a pattern wider than the range or cut of the machine. This manual adjustment is effected by means of the adjusting 85 screw 37^b (Fig. 8^a), which screw turns in a fixed nut 37^c on frame piece 35. On loosening the clamping bolts 37^a the latter may be raised or lowered to bring a new portion of the pattern or material within range of the 90 guide fingers and cutters respectively, whereupon the clamping bolts are again tightened. In this adjustment the point of the screw acts upon a fixed lug 37^d on the holder but after the adjustment is effected the point of the 95 screw is moved out of contact with the lug to a suitable distance to permit the automatic vertical movements of the holder, which will now be described. The vertical sliding bars 37 rest with their pointed lower ends upon the 100 peripheries of the heart shaped cams 38, to the end that when such cams are rotated the 105 holders will reciprocate vertically. Cams 38 are mounted on the shafts 39, and immediately back of such cams, are mounted the 110 worm wheels 40, which are engaged by the worm screws 41, mounted on the shaft 42, said 115 shafts revolving in boxes and the rotation of the cams 38 being due to the rotation of these shafts. On shaft 42 is mounted the miter 120 wheel 45, meshing with the miter 46 which has a spline pin in its hub and the grooved 125 shaft 47 slides through such hub, the pin thereof sliding in the groove of the shaft. In order that miter 46 may maintain its position 130 in relation to miter 45, and still slide over the grooved shaft 47 and during or after such sliding, still properly revolve shaft 47 and by such rotation communicate motion to the devices on both right and left standards, the 135 shaft is provided with boxes 48, 48, each rigidly projecting, one from the left and the other from the right standard as shown. The vertical frame upon the right side of table 15 is for the purpose of properly holding the material to be operated upon, and is in all details an exact counterpart of the left side device just described, with the exception of a ratchet wheel 54 and pawl 55, held on shaft 42, on the right side vertical frame (Fig. 1) and which is not necessary on the left side vertical frame.

On the under sides of the bases of each of the vertical frames are formed the racks b, b, b, b, the teeth of which project downward.

These teeth are engaged by the pinions *c, c, c* mounted on the shafts 49 and 50. Shafts 49 and 50, which are held in boxes formed on the side of the reciprocating table 15, carry 5 on their forward ends the hand wheels 51, 52. When it is found desirable to change the distance between the faces of the pattern and material holders, this can be quickly done by loosening the binding screws 53, (Figs. 3 and 10) then loosening the binding bolts in slides *a, a, a, a* and turning the hand wheels 51, 52 in the proper direction. As heretofore mentioned, the right hand side vertical frame has upon its shaft 42 the ratchet wheel 54, flanked 15 and overhung by the ratchet pawl 55, which ratchet pawl swings on shaft 42, and the teeth thereof engage the teeth of said ratchet-wheel. The pawl, as shown, is composed of two pieces. The upper one swinging on shaft 42, has lips 20 or lugs on both sides. The lower piece fits snugly between such lugs and can slide therein. This lower piece has formed upon its lower extremity two lugs which straddle a canting bar 56 and ride on such canting bar, 25 when the reciprocations of table 15 carries the ratchet pawl, of which it forms a part, forward or backward. The canting bar 56 is stiffly held by its journaled ends in boxes 57, 58. At a point on its lower edge is formed 30 the downward projecting lug 59, the outer face of which carries a rounded shoulder 60, (Figs. 1 and 4.) Inclosing the two flat sides of lug 59 is the swinging bifurcated lever 61, having on its inner side the rounded shoulder 62. Lever 61 is rigidly mounted on shaft 63, which shaft as heretofore mentioned, has mounted upon its opposite end the lever 20, which lever 20 is set in motion by the strikers 29, 30, when table 15 reciprocates.

40 From the above described construction it will be seen that if the table 15, with the devices thereon, is moved forward longitudinally, it will so advance until the striker 29 encounters the lever 20, causing such lever to 45 swing. In swinging the lever 20 will cause the shifting device to act whereupon the motion of the table will be reversed and continue such reversed motion until the striker 30 again reverses that motion by means of the 50 lever 20. Immediately the first motion of lever 20 sets in, the lever 61 on the same shaft is also set in motion and its rounded shoulder 62 encounters the shoulder 60 on lug 59, forcing such shoulder backward, thereby 55 canting the bar outwardly. Having canted such bar the lever 61 swings an additional distance sufficient to clear its lug from the canting bar lug, whereupon the canting bar will fall into its first position. The return 60 swing of straddle lever 61 will again cant the bar and allow it to fall, and this canting outwardly and inwardly will take place at the moment when the reversal of the sliding motion of table 15 is in process.

65 As heretofore stated, the lower end of ratchet pawl 55 rides forward and backward over canting bar 56. Its lugs closely fit the

sides of said bar. Consequently when such bar is canted the upper end of the lower section of the pawl will be thrown outwardly in 70 an arc, thereby elevating the upper section of the pawl in the manner as shown in Fig. 4. The teeth of pawl 55 having previously engaged the teeth of ratchet wheel 54, the pawl will cause such wheel to rotate. Having 75 reached its highest elevation the canting bar allows the pawl to drop into its first position and again engage upon the wheel; and thus during the termination of every reciprocation of table 15, rotate the shaft 42. This 80 rotation is communicated by the mechanism shown and heretofore described to all four of the heart shaped cams 38, which in turn simultaneously and equally raise the pattern and the material holders resting upon them 85 step by step at the termination of each reciprocating motion of the table 15 carrying them. After thus intermittently elevating such holders to the height of one and one-half inches, the rotations continuing, said cams 90 will step by step lower the holders to their starting point.

Upon the driving pulley 64 I mount the long belt 65 which extends upward and passes over a driving pulley 66 mounted in bearings 95 on the top of auxiliary frame D which auxiliary frame is formed upon and projects upward from within the main frame A. In its upward passage the belt 65 passes between the peripheral faces of a series of spindle rollers 67, (such rollers being one and fifteen thirty-seconds inches in diameter and held one and one-half inches from center to center) and a series of pressure rollers 68, of the same diameter and same distance between 100 centers and the centers of such spindle and pressure rollers being on the same horizontal plane. The several constructions are such that when the shaft 69, upon which the pulley 64 is mounted, is driven by the belt on the 105 driving pulley 100 (also mounted on shaft 69) at the rate of six hundred and twenty-five revolutions per minute, the spindles 70 in the rollers 67 will revolve at the rate of five thousand revolutions per minute. The said pressure 110 rollers are carried in separate bearings and held together in a housing and each is adjustable as to the space allowed to the said belt 65; thus the pressure exerted on each spindle roller can be accurately adjusted by 115 the particular pressure roller placed longitudinally opposite it. Passing through the series of rollers 67 are the cutter spindles 71, reciprocal therein, yet compelled to revolve with the rollers because of a pin in said 120 rollers which slides in a groove formed in the spindles. At one end each spindle carries the chuck head 72 (Figs. 1 and 4) which firmly holds a cutting tool. At the other end spindle 71 has two rigid collars 73, 74. Held 125 between these is the lipped collar 75. Fitting snugly between the lips of said collar and engaged by a bolt is the lever 76. Said lever has slotted ends and bolts in the lips engage

the slots and serve as points of leverage. Lever 76 is pivoted on the pivoted arm 77. To the arm 77 is pivoted an adjusting mechanism composed of the rod 78, the end of which is threaded and carries the thumb nut 82. Upon the rod is the collar 79, spiral spring 80, tightly compressed and held between the collar 79 and a rigid lug 81 formed upon a part of the auxiliary frame D. The purpose of this mechanism is to shift the position of the pivotal center of lever 76 when such shifting is desirable or necessary, the purpose of which will be hereinafter described. The end of lever 76, opposite to that end held between the lips of collar 75, is held in the same manner by a similarly lipped collar 83. Collar 83 passes around guide finger tube 84 and is held thereon with the rigid collar 85 and finger chuck 86. The shank of chuck 86 is tubular, is threaded on the outside and is firmly screwed into the guide finger tube 84, and forms a part thereof. The tubular shank of chuck 86 provides a socket of sufficient length to support the end of a steel rod when the tube carrying the chuck is either advanced or retracted. The series of guide finger tubes is held in flexible sleeves 87, which I prefer to make of soft cast rubber. They are placed in a vertical row as shown, and one and one half inches from center to center. Within the guide finger tube 84 is the compressed spiral spring 90, carried on the rod 88, which rod forms a part of the adjusting bolt 89 and its forward end passes freely into the chuck head shank. By means of the adjusting bolt 89, the compression of the spring 90, which is seated at one end against the inner end of the chuck shank and at its other end in a socket in adjusting bolt, is regulated, and the guide finger tube projected and held forward as desired. From the above description it will be seen that the finger tube, chuck, and finger held in the chuck, form one rigidly joined piece, and that such piece is projected and held forward by the spiral spring within the tube, in the manner described. On each side of the guide finger tube or spindle are adjusted the revolving traction rolls 91, 92, 93, and 94. These rolls are preferably made of hard wood or rawhide, with a core, the ends of which form journal bearings and are grooved in a manner that allows of a complete encircling of tube spindle 84 at two places thereon by the two sets of rollers. The adjustment is such that the surfaces of the rollers and tubes are almost in contact yet sufficiently distant to permit of a slight gyratory motion of the guide finger tube when pressure is brought to bear upon the side of the finger held therein, to the end that such partial gyration may establish traction contact. When no pressure is exerted upon the side of the guide finger the speed of the four rollers will not affect the tube spindle. The four traction rollers are geared in such a manner that they all revolve inwardly in a direction from the head of the spindle, the motion of such gear being

due to belt 65 running over pulley 66, the shaft of which pulley is connected by gear with the gearing of the rollers as shown. 70 When traction contact is established between said rollers and tubes the rollers will draw the spindle tube, chuck and guide finger forming part thereof backward against the projecting pressure of spiral spring 90 and this 75 backward motion will be more or less rapid, depending upon the extent and direction of pressure upon the side of guide finger. The function of the guide finger is to indicate, and in conjunction with the pattern employed, to control the depth to which the particular cutter connected therewith, shall cut into the material worked upon. Its gyratability, whereby backward motions may be effected, constitutes it a sensitive guide finger 80 in contradistinction to a rigid point or finger which might be drawn or lifted over the inequalities of a pattern by hand, or which if beveled sufficiently might be automatically drawn over an undulating surface. 85

The construction and application of a sensitive guide finger, *i.e.* a finger so constructed that slight pressure brought to bear upon its point or side of its rounded end would actuate mechanism which in turn would control the 90 distance of reciprocation of such a finger in itself, and of a cutter connected therewith, are disclosed and claimed in Patent No. 456,423, issued to myself and J. P. Bergeron July 21, 1891. These capabilities in a guide finger are 100 due to a construction whereby the finger is susceptible to pressure exerted against its point; and when such pressure is exerted the finger will move slightly backward; and when such motion ensues it actuates mechanism which 105 in turn changes the direction in which such finger and its particular cutter may have moved immediately preceding the moment of activity of such finger; and during the operation of the machine the distance of reciprocation of the cutters is under the constant control of said fingers, while I have in the invention herein described enhanced the capacity of the machine described in said patent, as well as the quality of work accomplished by it, by a construction wherein the sensitiveness of the guide fingers employed is due to the gyratability of such fingers. 110 The fingers thus constructed may when pressing upon a plane surface of any pattern become entirely disengaged from the reciprocating mechanism, thereby allowing the cutters to work better and smoother; and when such finger is encountered by a slight incline its partial gyration causes the tube, forming 115 part thereof, to attach itself to the reciprocating mechanism with sufficient force to allow the finger to rise agreeably to such incline, and with almost insensible reciprocations, the cutter controlled by the finger rising in the same manner and constantly cutting, the slightness of reciprocation permitting it to cut very smoothly. Finally when a 120 rectangular projection presses against the

side of the finger its partial gyrative motion will establish an immediate and firm traction contact with the reciprocating mechanism surrounding the finger tube whereby such 5 finger and its cutter will instantly rise to the full height of the rectangular mass encountered. Thus smoothness of surface, perfect duplication, and greater capacity are secured.

The essential differences between a sensitive 10 guide finger with a gyratory motion as herein-described and a finger such as described in said patent may be summed up as follows: The latter is for the purpose of governing or controlling distances of reciprocation of predetermined speed or speeds. On the other hand, the former is for the purpose of initiating, effecting and continuing every 15 variation of distance and of speed in its own reciprocation, or should the emergency arise cease all reciprocation and remain extended to the distance allowed of by the pattern employed.

The movements in a machine constructed as described are as follows: First,—the projection 20 of a guide finger and a cutting tool toward a pattern and a workable material. Second,—the movement of a pattern toward a guide finger until the point thereof rests upon the surface of the deepest depression 25 therein. Third,—the movement of material toward a cutter until enough material is advanced into the way of travel of cutter to insure a duplication of the highest parts of a pattern set in opposition thereto. Fourth,— 30 a clamping of a pattern and material in such positions. Fifth,—the rotation of a cutter or cutters. Sixth,—a longitudinal reciprocation of the pattern and material. Seventh,—an intermittent vertical movement of the 35 same. Eighth,—an undulating reciprocation of a cutter or cutters and a finger or fingers when an undulating surface of a pattern is traversed by a guide finger or guide fingers. Ninth,—a complete cessation of vertical motion 40 when a guide finger or fingers travel over a level plane in a pattern. Tenth,—a partial gyration of a guide finger or guide fingers when encountering a more or less abruptly 45 ascending surface in a pattern followed by a more or less pronounced reciprocation of such finger or fingers. Eleventh,—a quick 50 partial gyration when a guide finger or guide fingers encounter an abrupt projection at an angle with the line of travel of such finger or 55 fingers, and following thereon a speedy reciprocation continued until such obstruction is passed over. Twelfth,—a transverse receding motion of a guide finger or fingers when encountering a rectangular projection 60 squarely in the path of travel, followed by an instantaneous retraction or reciprocation of said finger or fingers. Thirteenth,—a correspondingly greater reciprocation and undulatory movement of a guide finger or guide 65 fingers, than of the cutter or cutters connected therewith, due to a previous adjustment for such particular effect. Fourteenth,—a cor-

respondingly greater reciprocation or undulatory movement of a cutter or cutters, also due to a previous adjustment for such particular effect. The second, third, and fourth motions are effected by hand in order to bring patterns and material in proper position before starting up the machine; all the other motions are automatic and due to the power 70 transmitted by the belts and gears. Fifteenth,—a manual adjustment of the pattern and material holders vertically when it is desired to reproduce a pattern wider than the 75 cut of the machine.

For the purpose of carving or duplicating a panel one foot wide, six feet long and one inch deep, the adjustment and operation of the machine are as follows: From a powershaft arranged to turn at the proper speed, I pass 80 a straight belt over the driver 4 on shaft 1, and a quarter turn or cross belt from the same shaft over the loose pulley 2 on shaft 1. I then run back the table 15 until the holders thereon have passed beyond the vertical 85 series of guide fingers. I turn one of the shafts 42 until the heart shaped cams 38 stand with their points upward, thereby bringing the panel and material holders to their highest altitude. I then fasten on the face of each 90 of the holders a piece of smooth planed board in the same altitude with cutters and guide fingers and upon these boards I test the machine after adjustment. I now fasten in each 95 of the guide tube heads by means of the friction collars 86 a guide finger. For work of the kind contemplated, such guide fingers are one and one fourth inches in length, one-half inch in diameter and taper to one-sixteenth of an inch at the point. The point as well as 100 the entire tapered finger is round, smoothly polished, and preferably of hardened steel. In the heads of the cutter spindles are fastened, by means of friction collars 72, the cutters. These cutters are in shape counterparts 105 of the guide fingers, but have a cutting edge formed on their entire length and the points are formed after the manner of a rounded spoon bit. These cutters and guide fingers are shown as a part of Fig. 5. I now set the 110 belt 65 in motion whereby the traction rollers 91, 92, 93, and 94 are revolved. I then bring forward the pressure rolls 68, one by one, until such belt is held against the peripheral faces 115 of the entire series of spindle rolls 67, whereupon the rolls and the spindles therein will revolve at proper speed. I then turn the table 120 15 forward until the testing boards on holders stand opposite the guide fingers and cutters. Having loosened the binding screws 53, 125 I now bring forward the faces of testing boards by turning the hand wheels 51 and 52, continuing such forward motion until one or all of the guide fingers and one or all of the cutter points just touch such boards. If, because 130 of an irregular length some of the cutters or fingers should not touch, I then turn the thumb nuts forming part of the adjusting mechanism of such particular cutter or guide finger,

whereby the same will immediately be brought into line. I now remove the testing boards and put in their stead the pattern and the material; run back the sliding table and advance the pattern and the material as far as the depth of cut to be effected. I then firmly clamp the vertical standards and also the strikers 29 and 30 in their proper positions, which for a pattern of the size contemplated would be at the ends of the rail 28. Thus arranged the adjustments are completed and the machine can be set in motion. The table 15 now reciprocates the length of the pattern; the guide points press upon and travel in a straight line over the same, the revolving cutters each cut a groove in the material. In this first travel of the table the guide fingers, chuck and tube will rise and fall as they pass over the undulations, and the cutters because 20 of their connections through lever 76 will rise and fall in corresponding undulations. If, instead of undulating surfaces the fingers encounter more abrupt projections, a slight side pressure will be exercised on such fingers and 25 a slight or partial gyration of the fingers, chuck and tube will occur which will be permitted by the flexible boxes 87 holding the guide tubes. The gyration will press and hold the guide finger tube in partial traction contact with the revolving rollers 91, 92, 93 and 30 94, and these will immediately assist in drawing the finger or fingers backward, thus causing them to ascend the surface of the pattern, the cutter or cutters connected to such finger 35 or fingers rising and falling correspondingly. Should the fingers in this first travel encounter rectangular projections in the pattern the effect of gyration and consequent binding on traction rolls will be immediate and positive 40 and the finger or fingers so encountered will be instantly withdrawn to the highest point of such projection, the cutter or cutters thereof describing the same movement. Finally should a finger or fingers travel upon a plane 45 surface there will be none of the movements just described, the adjustable spring 90 projecting the finger or fingers continually against such plane surface and the cutter or cutters will cut to a uniform depth. At the termination 50 of the first movement of the table just described, the four cams 38 will be slightly rotated by the pawl 54, allowing the pattern and material holders to descend one sixty fourth of an inch, more or less as may be desired, thus presenting a new profile for the 55 guide fingers to travel upon and cutters to reproduce. The table now reciprocates and the movement of fingers and cutters just described is repeated. Thus line after line is cut, each 60 cut overlapping the preceding cuts repeatedly as the diameter of the points of cutters are greater than the width of the quantity of material removed. All parts of the face of the pattern will in regular order be brought in contact with the ends or sides of guide fingers, and the cutters reproduce all its features. When the cams 38 have made a one-half ro-

tation the holders will have been lowered to a distance that will permit each guide finger and cutter to pass over the first line of travel 70 of the finger or cutter next adjacent thereto when the duplicate is finished, and requires even in the most artistic work only a little surface finishing and retouching. After the first adjustment the work of the attendant 75 consists in keeping the machine supplied with sharp cutters, and with material to be operated upon. He may attend to a number of the machines. At the speed herein specified, the maximum capacity of the machine is 80 sixty square feet of artistic carving or sculpturing per working day of ten hours. If a deeper and bolder duplicate is to be produced from a shallow cut pattern, which is often desirable, as shallow patterns can be more 85 cheaply made, it is only necessary to lengthen the distance from the central pivot of lever 76 to the pivot in the lipped collar on guide finger tube 84 by turning the thumb nuts 82 to the left, or if for any reason a shallower 90 duplicate is desired, the thumb nuts are to be turned to the right. After adjusting for any particular depth of cut, the fingers and cutters are brought up to line on the testing boards in the manner hereinbefore described. 95 If a pattern be wider than the cut of the machine the pattern and material holders may be raised or lowered so as to bring the surfaces not previously acted upon within the operative range of the machine, and a proper 100 joining of the cut surfaces may thus be effected.

In the preceding description the term "traveling" of guide fingers has been employed for sake of brevity. It should however be 105 understood that the guide fingers and cutters reciprocate from a rigidly fixed frame, the "traveling" motion being confined to the pattern and the material.

I claim—

1. In a duplicating machine, the combination with pattern and material holders arranged parallel to and facing each other, of cutting and guiding mechanisms operating conjointly therewith, means for automatically 115 moving said pattern and material holders longitudinally and vertically, whereby to progressively present the surfaces of the pattern and material to the guiding and cutting mechanism and said pattern and material holders being also manually adjustable in a plane transverse to the line of movement of the cutting and guiding mechanisms whereby to present new or additional surfaces of the same pattern and material to the action of the cutting and guiding mechanisms, substantially 120 as described.

2. In a duplicating machine, the combination with longitudinally and vertically reciprocating pattern and material holders arranged parallel to and facing each other and adjustable to and from each other of cutting and guiding mechanism operating conjointly therewith, said pattern and material holders 125

being also adjustable in relation to said cutting and guiding mechanism, substantially as described.

3. In a duplicating machine, the combination with a revolute and reciprocal cutter, of a reciprocal and gyratory guide finger, substantially as described.

4. In a duplicating machine, the combination with longitudinally and vertically reciprocating and variably adjustable material and pattern holders, of a series of revolute and reciprocal cutters and reciprocal and independently gyratory guide fingers, connected with the cutters, substantially as described.

15 5. In a duplicating machine, the combination with a revolute and reciprocal cutter, of a reciprocal and independently gyratory guide finger and a pivoted adjustable lever forming a connection between said cutter and finger, substantially as described.

20 6. In a duplicating machine, the combination with a series of revolute and reciprocal cutters, of a series of reciprocal and independently gyratory guide fingers and pivoted adjustable levers connecting the cutters and fingers, substantially as described.

7. In a duplicating machine, the combination with cutters and guide fingers connected by pivoted adjustable levers of mechanism 30 for adjusting said levers whereby to change the leverage upon said cutters and fingers, substantially as described.

35 8. A duplicating machine having an independently gyratory and reciprocal series of guide fingers and a series of revolute cutters connected therewith and controlled thereby, substantially as described.

40 9. In a duplicating machine, the combination with a series of revolute and reciprocal cutter spindles of rollers through which such spindles may slide and be revolved thereby, a series of pressure rollers arranged opposite thereof and a driving belt held by the pressure rollers in driving contact with the spindle rollers, substantially as described.

45 10. In a duplicating machine, the combination with revolute and reciprocal cutter spindles, of reciprocal guide fingers, tubes forming part of such fingers, lipped collars on the 50 cutter spindles and finger tubes, and levers having slot and pin connections with said collars, substantially as described.

55 11. In a duplicating machine, the combination with cutter spindles and guide finger tubes, of lipped collars having pins, a lever slotted at its ends and fitting between the lips on said collars and the pins of said lips engaging the slots of said lever and providing points of leverage, substantially as described.

60 12. In a duplicating machine, the combination with cutter spindles and guide finger tubes, of lipped collars held thereon, connecting levers movably held between such lips and arms whereon such levers are pivoted, substantially as described.

65 13. In a duplicating machine, the combina-

tion with cutter spindles and guide finger tubes, of connecting levers between said spindles and tubes, arms to which said levers are pivoted, said arms being also pivoted and adjusting rods pivoted to said arms, substantially as described.

70 14. In a duplicating machine, the combination with cutter spindles and guide finger tubes, of pivoted levers connecting said spindles and tubes, arms to which said levers are pivoted, rods pivoted to such arms, collars on said rods, spiral springs having a bearing on the collars and adjusting nuts, substantially as described.

75 15. In a duplicating machine, the combination with a cutter, of a guide finger connected therewith and adapted to control the movements thereof, and a spring arranged in connection therewith and adapted to constantly project said guide finger and thereby the cutter, substantially as described.

80 16. In a duplicating machine, the combination with a cutter, of a guide finger connected therewith and adapted to control the projection thereof into contact with the work, a spring arranged in connection with the guide finger to constantly project the latter, and means for adjusting the pressure of said spring, substantially as described.

85 17. In a duplicating machine, the combination with a reciprocating and rotating cutter, of a reciprocating guide finger connected therewith and adapted to control the movements thereof, and a spring arranged in connection with the guide finger to constantly project said finger, means for adjusting the tension of said spring and means for retracting the guide finger, substantially as described.

90 18. In a duplicating machine, the combination with a reciprocating and rotating cutter, of a reciprocating guide finger connected therewith and adapted to control the movements thereof, a spring arranged in connection with the guide finger and adapted to constantly project the same, and flexible bearings for said guide finger whereby it is permitted a gyrating motion, substantially as described.

95 115 19. In a duplicating machine, the combination with a guide finger and tube to which said finger is connected, a spiral spring arranged in said tube and having a bearing thereon and a rod passing through the axis of the spring and having a sliding bearing in the tube, said rod being adjustable whereby to tension the spring, substantially as described.

100 120 125 20. In a duplicating machine, the combination with gyratory guide fingers, of flexible bearings for said fingers, springs for projecting the guide fingers and traction rolls for drawing back such fingers after the gyratory motion sets in, substantially as described.

130 21. In a duplicating machine, the combination with a reciprocating carriage for the pattern and material holders, of mechanism for reciprocating the carriage, and shifting mech-

anism for changing the direction of travel of such carriage, substantially as described.

22. In a duplicating machine, the combination of a reciprocating carriage, mechanism for reciprocating the same, stops for limiting the travel of the carriage and a pivoted canting lever for operating the shifting devices of such carriage, substantially as described. 45

23. In a duplicating machine, the combination with a reciprocating carriage and driving belts, a shifting mechanism for said belts, stops for operating said shifting mechanism, said stops being carried by and adjustable on such carriage, substantially as described. 50

15 24. In a duplicating machine, the combination with a reciprocating carriage, of sliding and adjustable standards thereon carrying pattern and material holders and means for sliding and adjusting such standards, substantially as described. 55

25 25. In a duplicating machine, the combination with a reciprocating carriage, of adjustable and sliding standards, and adjustable clamping pieces for said standards, substantially as described. 60

26. In a duplicating machine, the combination with sliding standards, carrying pattern and material holders, cams on which said standards rest and means for rotating said standards whereby to move said standards, substantially as described. 65

30 27. In a duplicating machine, the combination with adjustable and sliding standards, of cams for moving the standards and worm gear- 70
35 ing for moving the cams, substantially as described.

28. In a duplicating machine, the combination with the reciprocating carriage, of gearing for moving the carriage, shifting mech- 75
40 anism for the gearing, sliding standards car-

rying pattern and material holders, cams for moving the standards and means controlled by the shifting mechanism for operating said cams at the end of each reciprocation of the carriage, substantially as described. 45

29. In a duplicating machine, the combination with a reciprocating carriage, of driving mechanism therefor, a shifting device for the driving mechanism, vertically movable pattern and material holders and means controlled by the shifting mechanism for moving the pattern and material holders, substantially as described. 50

30. In a duplicating machine, the combination with a revoluble shaft, of a ratchet wheel, 55 swinging pawl, and a canting bar provided with projecting lug, substantially as described.

31. In a duplicating machine, the combination with a revoluble shaft, of a ratchet wheel, 60 swinging pawl, canting bar and lug, and a pivoted swinging arm provided with a lug to encounter the lug on said canting bar, substantially as described.

32. In a duplicating machine, the combination with a revoluble cam, of X-shaped bars bearing on said cams and grooved standards in which said bars slide, substantially as described. 65

33. In a duplicating machine, the combination with revoluble cams, of X-shaped bars resting with one end against the peripheries of said cams, and a table or holder sliding upon such bars and adjustable thereon, substantially as described. 70
